UNITED STATES PATENT OFFICE.

QUENTIN D. CORLEY, OF DALLAS, TEXAS.

ELBOW-JOINT FOR ARTIFICIAL ARMS.

1,273,461.

Specification of Letters Patent. Patented July 23, 1918.

Application filed April 9, 1917. Serial No. 160,661.

To all whom it may concern:

Be it known that I, QUENTIN D. CORLEY, citizen of the United States, residing at Dallas, in the county of Dallas and State of Texas, have invented certain new and useful Improvements in Elbow-Joints for Artificial Arms, of which the following is a specification.

This invention has particular relation to self locking elbow-joints for artificial arms.

The primary feature of the invention is to provide a joint for those who have amputations above the elbow and to arrange said joint so that it may be manipulated by a flexible connection from the shoulders of the wearer and its arm members locked in substantially any desired adjustment without the aid of outside assistance and entirely by the use of the flexible connection.

In carrying out the invention a forearm member is hinged to the upper-arm member and means provided whereby the two members may be locked either in line or in the various angular adjustments which a

natural arm would assume in holding articles or performing other functions, the said means being entirely under the control of a flexible connection attached to the shoulders of the wearer and also being of such a nature as to release the parts automatically when the connection is placed under tension and to automatically and expeditiously lock the parts when tension on said connection is relieved.

The invention will be more readily understood by a perusal of the following specification and by reference to the accompanying drawing, in which an example of the invention is shown and wherein:

Figure 1 is a plan view of an artificial arm constructed in accordance with the invention,

Fig. 2 is a side elevation of the same, and Figs. 3 and 4 are details of the locking parts.

In the drawings the numeral 1 designates a forearm member and 2 an upper-arm member hinged together to form an elbow-joint. The forearm member comprises two

side bars 3 connected at the lower end of the arm by a plate 4 against which a housing 5 is arranged between the bars. These parts 4 and 5 provide means to which a suitable artificial hand or similar appliance may be attached in a suitable manner.

At the opposite ends of the bars integral

locking disks 6 are provided, each having a marginal aperture 7 in closely spaced order. These register with corresponding disks 8 having marginal apertures 10 arranged in closely spaced order and to register with the apertures 7. The disks 8 are integral with the lower ends of side bars 9 forming part of the upper-arm member and secured to the sides of an arm socket 11.

The disks are centrally pivoted on trunnions 12 carried by a cross bar 13 extending between the disks 6. A lever 14 is pivoted on the cross bar and has slots 15 receiving the upturned ends of plunger-pins 16 mounted in brackets 17 on opposite sides of the cross bar. The pins have stops 18, each engaging one of the brackets and receiving one end of a coiled spring 19 having its other end abutting the other bracket. These spring pressed pins pass through the apertures 7 and engage in the apertures 10. Covering disks 19' mounted on the trunnions conceal the apertures 10 and the ends of the pins.

It will be seen that by swinging the lever 14 in the direction of the arrows the pins will be withdrawn from the apertures 10 permitting the arm members to be freely adjusted, the dot and dash lines in Fig. 2 indicating the center lines of positions to which the forearm may be swung. A housing 20 is fixed between the bars 1 adjacent the housing 5 and has a bell-crank lever 21 pivoted on the underside of its top. This lever has an upstanding stud 22 engaging the curved end of the lever 12. The opposite end of the lever 21 extends laterally in the housing 20 and terminates in an upturned ear 23 projecting through an arcuate slot 24 in said housing. This slot limits the movement of the lever 21. A cord 25 extends from the ear under a roller 26 mounted in a bracket 27 on the side of the bar 3 and over another pulley 28 mounted in a bracket 29 on the corresponding side bar 9 of the member 2. A pulley 30 is mounted on the opposite side of the joint and forms a guide for a cord (not shown) for operating an artificial hand.

The upper end of the cord 25 is suitably attached to the shoulders of the wearer in a manner well known in this art. The wearer by moving his shoulders may place the cord under tension and exert a pull thereon whereby the lever 21 is swung and the pins 16 withdrawn from the apertures 10; and

with the parts in this position he may by a continued pull swing the forearm upward by slightly relieving the tension permit the forearm to swing down by its own weight.

5 By a sudden release of the cord the pins are freed and will spring into the next apertures encountered; by reason of the slots 15 the pins may lock independently.

10 The foregoing description and illustration clearly express the invention, but it is to be understood that said illustration is merely an exemplification and the invention may be carried out in various other ways.

What I claim, is:

15 1. In an elbow joint for artificial arms, an upper arm member, a forearm member hinged to the upper arm member, spring actuated means for locking the arm members in adjusted positions, a lever for operating said locking means against the tension of its spring to withdraw said means, and a shoulder controlled flexible connection attached to said lever for swinging the same to withdraw the locking means and to hold the latter in 20 this position while swinging the forearm, said connection by a sudden relaxation thereof releasing the lever and permitting the spring of the locking means to operate the latter.

30 2. In an elbow-joint, two arm members hinged together, and laterally and oppositely operating locking devices penetrating the members at their hinge points.

35 3. In an elbow joint for artificial arms, an upper arm member, a forearm member hinged to the upper arm member, a support at the joint between said arm members, having a plurality of stops, a pair of spring projected pins mounted on said support and engaging 40 the stops, a lever pivoted on the support and engaging said pins on opposite sides of its pivot point, a bell-crank lever carried by the forearm and having one leg engaging the lever, a flexible connection attached to the

other end of said bell-crank lever, and 45 guides on the arm members over which the connection passes.

4. In an elbow-joint, two arm members, spring projected locking pins carried by one member and engaging the other member, 50 means for withdrawing the said pins to free the members, and a shoulder actuated flexible connection connected with said withdrawing means.

5. In an elbow-joint, two arm members, 55 spring projected locking members penetrating the arm members, a lever for withdrawing said locking members, means for actuating the lever, and a shoulder controlled flexible connection attached to the actuating 60 means.

6. In an elbow joint for artificial arms, an upper arm member, a forearm member hinged to the upper arm member, a spring actuated locking device carried by the forearm member and engaging the upper arm member, an operating device carried by the forearm member and engaging the locking device for withdrawing the same, and a flexible connection attached to the operating device 70 and serving to manipulate the same and hold the locking device withdrawn, said flexible connection also serving to swing said forearm member.

7. In an elbow joint for artificial arms; 75 two arm members hinged together; a locking device mounted on one of the members and including oppositely directed spring extended pins engaging the other arm member, a centrally pivoted member engaged by 80 the pins on each side of its pivot point, a bell-crank lever having engagement with the pivoted member; and a flexible connection attached to the other end of the lever.

85

In testimony whereof I affix my signature.

QUENTIN D. CORLEY.
